(57) CLAIM

The ornamental design for a bar clamp, as shown and described.

DESCRIPTION

The nature and intended use of the article in which the design is embodied is that of a dual-purpose clamp having jaws that may be oriented to face towards or away from each other. The bar clamp may be used to clamp workpieces together when the jaws face towards each other, or to spread workpieces apart when the jaws are reversed and face away from each other.

FIG. 1 is a perspective view of a bar clamp showing my new design;

FIG. 2 is a front view thereof;

FIG. 3 is a side elevational view thereof; and,

FIG. 4 is a top view thereof.
